UNITED STATES PATENT OFFICE

GEORGE BODEN, OF WATERBURY, CONNECTICUT, ASSIGNOR TO SCOVILL MANUFACTURING COMPANY, OF WATERBURY, CONNECTICUT, A CORPORATION OF CONNECTICUT

LOCKING DEVICE FOR WINDOW SCREENS

Application filed January 21, 1930. Serial No. 422,328.

This invention relates to extension or expandible window screens, ventilators, and analogous extension and expandible articles.

It is an object of the invention to provide locking means for preventing movement of the screen or other sections from their adjusted or predetermined position.

It is another object of the invention to make provision for the release of the locking means.

It is a further object of the invention to provide a locking means for screens or the like which is positive in action, simple in construction, and reliable in service and operation.

With these general objects in view, the invention consists in the features, combinations, details of construction and arrangements of parts which will first be described in connection with the accompanying drawings and then more particularly pointed out.

In the drawings—

Figure 1 is a perspective view, with parts broken away and in section, of an expandible screen having locking means of the invention applied thereto;

Figure 2 is a longitudinal section in direction of arrow 2 of Figure 1;

Figure 3 is a similar sectional view showing manual release of the locking means;

Figure 4 is a cross-section as on line 4—4 of Figure 1; and,

Figure 5 is an isolated perspective view of a locking element constructed in accordance with the present invention.

Referring to the drawings, the invention is exemplified with a screen and the screen illustrated as an example comprises two wooden frame sections. One section, which may be termed the inner section, comprises a top bar or moulding 5 and a bottom bar 6 connected at one end by an end strip 7. The other section, which may be termed the outer section, comprises corresponding top, bottom and end pieces 5^a, 6^a, and 7^a. At the overlapping ends, the frames are open.

Suitably secured in the frame are screens proper 8, 9, of wire mesh or other suitable material. At the open ends of the frame, the screens have finishing strips 10, 11. Ex-

treme open position of the screen is fixed by the mutual engagement of these finishing strips. Extreme closed position is fixed by the engagement of the top and bottom bars of one frame section with the end strip of the other, said end strips being thicker than the other strips to provide stop shoulders.

In the construction illustrated, the two frame sections have complementary grooves for receiving individual bearing elements. The inner section has one or more bearing elements, slideable in the groove of the outer section, and the outer section has one or more bearing elements slideable in the groove of the inner section.

In the exemplification here illustrated, the top bar 5 has a dovetail groove 12, undercut upwardly and downwardly, as appears in Figure 4. The top bar 5^a has a similar but reversely faced groove 12^a. Anchored in the open end of groove 12 is a bearing element 13 having a portion arranged to slide in groove 12^a. A similar bearing element is anchored in the open end of groove 12^a to slide in groove 12. These bearing elements may advantageously be of the type disclosed in my pending application, Serial No. 339,769, filed February 14, 1929.

The invention in its entirety includes a locking element slidably disposed in the groove of one section and extending in the path of the other section to be urged automatically into locking engagement with the first section upon tendency of said sections to move relatively in one direction. In this embodiment, the locking element acts to prevent movement of the screen sections such as to decrease the effective screen area. Although capable of various constructions, in that here shown as an example, the locking element is tiltable and provided with teeth for embedding in one section. As shown, said element is of metal and comprises a flat foot 15 slideable in the dovetail groove of one section and fitting in the undercut sides thereof, said foot being free for sliding movement in said groove but wide enough not to fall out. This foot has, in effect, a sliding tenon and mortise joint with said section. The locking element further includes a projecting part

16 connected to the foot by a bend 17 forming a heel. The projecting part is narrowed along its sides relative to the foot so as to be accommodated in the narrow portion of the groove. As shown, a strengthening rib 18 extends across the corner between the foot and projecting part. The free end of the foot has teeth 19 directed generally oppositely to the projecting part and toward the section, in the groove of which said foot is positioned. The locking element is inserted in the groove by sliding the foot in at the end of the groove.

In this practical exemplification, the projecting part 16 is oblique to the foot 15 and defines the obtuse angle therewith. The locking element is arranged in a groove of one screen section beyond the rear end of the other section and with the projecting oblique part slanting toward said rear end. Tendency of the sections to move relatively in a manner to decrease the effective screen area causes said rear end to act on the projecting oblique part and to tilt the locking element, whereby the teeth are embedded in fixed engagement with the first screen section. The locking element, being thus fixed, prevents such movement of the sections, the projecting part acting as a stop.

30 Provision is made for releasing the locking element whereby it may be held in its released position so that the screen sections may be moved to decrease the effective screen area. This is accomplished, in the present example, by an off-set 20 at the end of the projecting oblique part. As here shown, this off-set extends from the projecting oblique part in a direction generally opposite to the foot and overlaps the rear end of the complementary screen section when engaging said projecting part. The off-set may be depressed by the thumb or finger (Figure 3) to tilt the locking element and withdraw the embedded teeth from the locking engagement. By maintaining such depressed condition, the teeth may be held out of locking engagement and the screen sections slid freely in either direction and adjusted to a desired position.

50 The locking element may be employed, for example, on the inside of an extension screen to maintain a predetermined adjustment of the screen and to prevent opening thereof from the outside, while permitting release from the inside. These elements may be applied to extension articles to prevent expanding or contracting movement of sections or both.

What is claimed is:—

60 1. The combination with relatively movable sections, of a locking element slidably disposed in a groove of one section and extending in the path of another section to be urged automatically thereby into locking engagement with the first section.

2. The combination with relatively movable sections, of a tiltable locking element having a foot slidably disposed in undercut sides of a groove of one section and having a part projecting in the path of another section, said foot having means for locking engagement with the first section.

3. The combination with relatively movable sections, of a tiltable locking element having a foot slidably disposed in undercut sides of a groove of one section, a part projecting in the path of another section and extending obliquely from the foot and having an obtuse angular connection with the foot at one end thereof, the locking element being arranged so that the projecting part slants toward said other section, and teeth at the free end of the foot directed toward the first section.

4. The combination with relatively movable sections, of a locking element slidably disposed in a groove of one section and extending in the path of another section to be urged automatically thereby into locking engagement with the first section, said locking element having means for effecting its release manually.

5. The combination with relatively movable sections, of a tiltable locking element having a foot slidably disposed in undercut sides of a groove of one section and having a part projecting in the path of another section, said foot having means for locking engagement with the first section, and an off-set on the free end of the projecting part for effecting manual release of the locking engagement.

6. The combination with relatively movable sections, of a tiltable locking element having a foot slidably disposed in undercut sides of a groove of one section, a part projecting in the path of another section and extending obliquely from the foot and having an obtuse angular connection with the foot at one end thereof, the locking element being arranged so that the projecting part slants toward said other section, and teeth at the free end of the foot directed toward the first section, and an off-set on the free end of the projecting part for tilting the locking element manually.

7. A tiltable metallic locking element comprising a foot having teeth at one end and a part projecting from the other end of said foot in a general direction opposite to the teeth, said projecting part having an obtuse angular connection with the foot, and an off-set on the free end of the projecting part.

8. A tiltable metallic locking element comprising a foot having teeth at one end and a part projecting from the other end of said foot in a general direction opposite to the teeth, said projecting part having an obtuse angular connection with the foot, and an off-set on the free end of the projecting part.

9. A tiltable metallic locking element comprising a foot having teeth at one end and a

part projecting from the other end of said foot in a general direction opposite to the teeth, said projecting part having an obtuse angular connection with the foot, and an off-set on the free end of the projecting part, said off-set extending from the projecting part in a direction generally opposite to the foot.

10. The combination with relatively movable sections, of a tilttable locking element having a foot slidably disposed in undercut sides of a groove of one section, a part projecting in the path of another section and extending obliquely from the foot and having an obtuse angular connection with the foot at one end thereof, the locking element being arranged so that the projecting part slants toward said other section, and teeth at the free end of the foot directed toward the first section, and an off-set on the free end of the projecting part for tilting the locking element manually, said off-set extending from the projecting part in a direction to overlap said other section when engaging the projecting part.

11. The combination with relatively movable sections, of a loose, freely tilttable locking element capacitated to be tilted automatically by one section into locking engagement with another section.

12. A freely tilttable locking element having a foot with locking teeth and a part projecting from said foot for tilting the foot and acting as a stop.

In testimony whereof, I have hereunto set my hand.
